UNITED STATES PATENT OFFICE

SYLVESTER J. TUCKER, OF RICHMOND, VIRGINIA.

PERCENTAGE-CALCULATOR.

SPECIFICATION forming part of Reissued Letters Patent No. 10,511, dated August 12, 1884.

Original No. 291,817, dated January 8, 1884. Application for reissue filed April 1, 1884.

To all whom it may concern:

Be it known that I, SYLVESTER J. TUCKER, of Richmond, in the county of Henrico and State of Virginia, have invented a new and useful Improvement in Percentage-Calculators, of which the following is a full, clear, and exact description, reference being had to the annexed drawing, forming part of this specification.

This invention relates to devices for reducing common fractions to decimals, to be used by railway and other transportation companies for determining percentages and proportions in dividing rates, revenues, or expenses on the basis of mileage; and the invention, with these ends in view, consists, essentially, of a plurality of graduated scales and a suitable marking device or devices, the novel construction of which will be hereinafter described and claimed.

The drawing is a diagram of my improved calculator, in which A indicates a stationary triangle, having a percentage-scale, B, arranged along its hypotenuse; and C is a similar triangle, which is fitted to slide in the triangle A, and is likewise provided with a scale, D, arranged along its hypotenuse, which latter scale represents a series of numbers the percentage of which is to be ascertained.

The numbers in the scales B and D increase in denomination from the right hand upward to the left hand, the former extending from 0 to 100, and the latter from 0 to 1,000, or from 0 to any number higher than 1,000, according to the value given to the graduations. If each graduation is made to count two instead of one, the scale D will indicate 2,000 as the highest number. I have shown the scale D marked off to indicate both 1,000 and 2,000 at the termination of the scale, using two sets of numbers, one the double of the other, to mark the graduations. When the scale D is moved against the scale B, the graduations of the two will exactly register with each other, and the percentage numbers will correspond with the numbers whose percentage of one thousand or two thousand they (the former) represent.

The movable triangle C is provided with a slot, E, and the stationary triangle with a set-screw, F, by means of which it (the movable triangle) may be adjusted with respect to the stationary triangle and held in any given po-

sition. The stationary triangle is provided at its left-hand side with a stretched cord, G, or equivalent device, which serves as a marker on the scale D. This cord is connected to set-screws H I on the triangle, and is arranged at right angles to the base J of the stationary triangle. A second cord, K, or equivalent device, is attached to a collar, L, which is loosely mounted on a screw, I, at the apex of the right angle of the stationary triangle, and is connected at its other end, by a set-screw, O, to a slide, P, which moves on a segmental bar, Q, the arc of which is drawn from the pin or set-screw I. One of the uses of the cord K is to mark the percentage on the scale B and another use is to mark the numbers on both scales, as will be hereinafter explained.

The operation of the calculator is as follows: If it is desired to ascertain what is seventy per cent. of fourteen hundred, the scale D is moved out from the scale B until the cord G marks "1,400" on the upper edge of the scale D. The cord K is then moved to a position to mark "70" on the lower edge of scale B, in which position it will also mark "980" on the upper edge of scale D, as seventy per cent. of fourteen hundred. The same position of the cords, as shown in the drawing, also indicates 490 as seventy per cent. of seven hundred.

It is obvious from the above that if the percentage of several numbers aggregating fourteen hundred is desired, and 980 is one of these numbers, the percentage will be indicated by the cord K. In like manner the percentage which any part of fourteen hundred bears to the whole will be indicated on scale B by moving the cord K to a position to mark that part of fourteen hundred on the scale D. Such is the operation where an equal percentage is allowed to a given number of railroads, for example; but where an "arbitrary" percentage is required by one of such roads, this percentage must be deducted and the remainder divided equally among the remaining roads. In such case the cord K serves to mark the numbers on both scales. For instance, if one road requires thirty per cent. and the remaining seventy per cent. is to be divided equally among the remainder of a given number of roads, the cord K is to be moved to a position in which it will mark "70" on scale B. Now, if the sum total in miles is twelve hundred, and

two hundred and twenty of these belong to the road requiring thirty per cent., two hundred and twenty are to be deducted from twelve hundred, and the movable triangle is to be moved outward until the remainder, "980," is marked on scale D by cord K. Then, if the cord K is moved to positions to mark on scale D the respective numbers of miles of the remaining roads whose sum total is nine hundred and eighty, the several proportions of seventy per cent. coming to the said remaining roads will be indicated on scale B by cord K.

What I claim is—

1. In a percentage-calculator, the combination, with a plurality of graduated scales capable of adjustment with respect to each other, of a suitable marker capable of being moved to register with such scales, the whole being arranged so as to ascertain an arbitrary percentage, substantially as described.

2. In a percentage-calculator, the combination, with a plurality of graduated scales capable of adjustment with respect to each other, of stationary and movable markers, the latter capable of being moved to register with such scales, and the whole arranged so as to ascertain a given per cent., substantially as described.

3. In a percentage-calculator, the combination, with a plurality of triangles capable of adjustment with respect to each other, and having respectively mileage and percentage indicating scales, of a movable marker capable of being moved to register with such scales, so as to ascertain an arbitrary percentage.

4. In a percentage-calculator, the combination, with a plurality of triangles having graduated scales on their hypotenuses, of a marker capable of being moved to register with such scales.

5. In a percentage-calculator, the combination, with a plurality of triangles having grad-

uated scales, of stationary and movable markers, the latter capable of being made to register with such scales.

6. In a percentage-calculator, the combination, with a plurality of triangles having graduated scales on their hypotenuses, of stationary and movable markers, the latter capable of being made to register with such scales.

7. The combination of the stationary and the movable triangles having graduated scales and numbers, as described, and the movable marker, substantially as shown and described.

8. The combination of the stationary and the movable triangles having graduated scales and numbers, as described, and the movable marking-cord and segmental guide for the same, substantially as shown and described.

9. The combination of the stationary and the movable triangles having graduated scales and numbers, as described, and the movable and stationary markers, substantially as specified.

10. The combination, with the triangles, of the movable marking-cord, the loose collar and pin for securing it at one end, and the slide and segmental guide at the other end, substantially as shown and described.

11. The combination of the stationary triangle, the movable triangle having a longitudinal slot in its base, and the set-screw for adjusting and holding said triangles in any desired relation to each other, substantially as shown and described.

12. The combination of the stationary triangle, having the percentage-scale B arranged along its hypotenuse, the movable triangle having the number-bearing scale D arranged along its hypotenuse, and the markers, substantially as specified.

SYLVESTER J. TUCKER.
